COAT HOOK

La Verne E. Clayton, Rockford, Ill., assignor to Amerock Corporation, Rockford, Ill., a corporation of Illinois

Filed Nov. 2, 1961, Ser. No. 67,362

Term of patent 14 years

(Cl. D17—12)

FIGURE 1 is a perspective view showing my new design for a coat hook.

FIG. 2 is a top view.

FIG. 3 is a side view of the coat hook.

FIG. 4 is an enlarged sectional view taken along the line 4—4 in FIG. 3.

FIG. 5 is a front view of the coat hook.

FIG. 6 is an enlarged sectional view taken along the line 6—6 in FIG. 3.

The design is particularly characterized by the length of the base relative to the lengths of the hooks, by the

comparatively wide ends of the hooks, by the cross-sectional shape of the hooks and the base to provide a central ridge and by the gentle reverse curvature of the upper hook.

I claim:

The ornamental design for a coat hook, substantially as shown and described.
